Primary Examiner — Jack Reickel*Assistant Examiner* — Sydney M Evans(74) *Attorney, Agent, or Firm* — Birchwood IP(57) **CLAIM**

The ornamental design for a magnetic holding strap, as shown and described.

DESCRIPTION

FIG. 1 is a front, right and bottom perspective view of a magnetic holding strap, showing my new design;

FIG. 2 is a rear, left and top perspective view thereof;

FIG. 3 is a front, right and bottom perspective view of the magnetic holding strap in a folded state;

FIG. 4 is a front view thereof;

FIG. 5 is a rear view thereof;

FIG. 6 is a left side view thereof;

FIG. 7 is a right side view thereof;

FIG. 8 is an enlarged top plan view thereof; and,

FIG. 9 is an enlarged bottom plan view thereof.
